SHUTTLE CONTROL FOR SHUTTLE CHANGING FILLING MIXING LOOMS

Richard G. Turner, Worcester, Mass., assignor to Crompton & Knowles Loom Works, Worcester, Mass., a corporation of Massachusetts

Original application May 3, 1934, Serial No. 723,730. Divided and this application October 23, 1934, Serial No. 749,581

8 Claims. (Cl. 139—232)

This application is a division of my co-pending application Serial No. 723,730, filed May 3, 1934.

This invention relates to improvements in filling mixing looms and it is the general object of the invention to provide a shuttle changing loom 5 in which single picks of filling can be mixed.

When weaving a plain fabric in a loom operating with but one shuttle objectionable shading is likely to result due to the fact that successive supplies of weft may not be exactly alike either 10 as to size or color. Heretofore this has been corrected by using two or more shuttles which run in alternation to mix their respective wefts. When such looms have been made weft replenishing 15 it has been customary to weave two picks of one bobbin followed by two picks of another.

Where very coarse yarns are used the variation in size is likely to be considerable, and with prior practice a ribbed effect may occur. In non-automatic weaving it is customary to weave such 20 a fabric on a so-called 2 by 2 loom having two shifting shuttle boxes at each end of the lay. The shuttles are picked in a regular sequence and follow each other in rotation being each active for a single pick.

In rendering a 2 by 2 loom automatic as to weft supply, I prefer to use a shuttle changing mechanism rather than a bobbin changer. In my co-pending application Serial No. 460,746 I show 25 shifting shuttle boxes at each end of the lay, those at the magazine end shifting only at the time of renewal of weft supply. Because of these boxes at the magazine end, I find that by adding 30 to them an extra cell, I can operate in the usual manner for a 2 by 2 loom, and have an abnormal shift at the time of shuttle change. This modification of a principle already proposed by me is 35 found to operate satisfactorily. The three weaving shuttles all carrying the same kind of weft arrive in regular order in the top shuttle box at 40 the magazine side and can be replaced by shuttles drawn from the magazine. All the reserve shuttles in the magazine have weft of the same kind, so that a single stack of shuttles will suffice.

It has been proposed heretofore to use so-called pick and pick automatic looms having provision for replenishing any one of several shuttles where any shuttle can be active on any pick for one pick only, if desired. The sequence of 45 shuttles already referred to is a specific case of the automatic pick and pick type of loom referred to, examples of which are found in Patent No. 1,674,860 of June 26, 1928 to Gordon and Patent No. 1,605,271, November 2, 1926 to Nelson. In 50 such looms, where it is desired, the color can be

the same for all the shuttles and pick and pick cloth can be woven automatically by two, three or more shuttles, depending upon the capacity of the loom.

Such looms are bobbin changers, however, and 5 have certain undesirable features. The shuttle is not threaded on the first pick across after transfer and because of this fact the weft is loose and is likely to leave a mark in the cloth. Furthermore, the outgoing bobbin will usually 10 have its trailing end threaded in the shuttle eye to be drawn back into the shed on the first pick after transfer and there are likely to be short double picks unless some special provision is 15 made for handling the thread ends at the time of transfer. In bobbin changing looms also it is necessary to have a cutter in addition to the selvage trimmer, to remove the thread of the outgoing bobbin which remains threaded in the shuttle. 20

There is still another condition existing in 25 bobbin changing looms which renders desirable an alteration in the change of the center filling stop motion. In looms employing shifting boxes at both ends it is desirable to have a center stop motion to detect weft every beat of the loom, and the stop motion should be as near the center of 30 the cloth as possible, so that detection on all picks will be the same. The thread holder of a bobbin magazine must be set back far enough to assist 35 shuttle threading, and in many looms is in the same vertical plane as the fell of the cloth. As the lay moves backwardly the weft will be oblique with respect to the fell, starting from a point considerably behind the fell at the magazine end and leaving the shed at a point much farther 40 behind the fell on the side remote from the magazine. The tines of the center filling fork will ordinarily not be able to reach this pick should the stop motion be central of the lay, and in order 45 to detect on the transferring beat the stop motion is moved off center in a direction toward the magazine. This results in an uneven character of detection, permitting the fork to be held up by a short end extending in from the magazine end. Should the new thread break at transfer and a thread end drawn in by the shuttle, such end might reach the offset fork to support it, and a shift of boxes would permit weaving past 50 the mispick.

When using shuttle changing looms the threading, pulled-in ends, cutting, and stop motion defects are eliminated. The reserve shuttles are 55 fully threaded, hence the thread holder can be

placed considerably in advance of the fell, and the first pick after change will have the same relation to the stop motion as all other picks. The center stop motion can therefore be placed centrally of the cloth. In shuttle changing looms the outgoing shuttle carries its thread with it, and there is no necessity for cutting at any point other than at the selvage trimmer. This latter can take place several picks after the change. Furthermore, there is no opportunity for pulled in ends.

In the loom described more particularly hereinafter there are two weaving shuttle boxes at each end of the loom which cooperate with three weaving shuttles to place the shuttles in active position according to a regular sequence with each shuttle active for but one pick. A magazine of reserve shuttles is supplied at one end of the loom and there is located at that end an auxiliary shuttle box which normally does not take part in the regular sequence but which is placed in the path of a depleted shuttle which is moving toward the magazine. The means which accomplishes this placing of the auxiliary shuttle box also moves one of the regular weaving boxes into a position where it can receive a fresh shuttle from the magazine. The general shuttle changing operation may be substantially the same as shown in my previously mentioned application but one of the weaving shuttle boxes will be located between the auxiliary box and the box which receives fresh shuttles from the magazine.

It is another object of my invention to extend the interval of complete shuttle change so that the movement of the boxes at the magazine end of the loom will be short and this result I accomplish by operating according to a method whereby a shuttle can be picked from the magazine end during the interval occupied by shuttle change, this shuttle being purposely located at the magazine end to facilitate shuttle change although it takes no part in the actual exchange of shuttles.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a side elevation of the detector end of the loom, the shuttle boxes and part of the lay shown in section,

Fig. 2 is a side elevation of the opposite side of the loom showing a single color magazine, with parts in section,

Fig. 3 is a view similar to the upper part of Fig. 1 but with the detector in a different position,

Fig. 4 is a plan view looking in the direction of arrow 4, Fig. 3,

Fig. 5 is a diagrammatic view showing a series of shuttle relations setting forth the normal sequence in which the shuttles are picked,

Figs. 6 and 7 show the structure set forth in Fig. 2 in different positions and on a smaller scale,

Fig. 8 is an enlarged vertical section through the shuttle boxes and part of the lay at the magazine end of the loom,

Fig. 9 is a front elevation in the direction of arrow 9, Fig. 8, and

Fig. 10 is a detail vertical section on line 10—10, Fig. 2.

Referring particularly to Fig. 1, I have shown

a loom frame 10 and a lay 11 mounted on swords 12. A top shaft 13 moves connectors 14 to reciprocate the lay. A pair of upper and lower shuttle boxes 16 and 17, respectively, are mounted on the upper end of a box rod 18, the lower end of which is connected to a lifting link 19 operatively related to a cam lever 20. The lever is pivoted at 21 to the loom frame and has a roll 22 to cooperate with a box lifter cam 23. The latter moves with a gear 24 mounted on a stub shaft 25 and meshing with a gear 26 of half its size on the bottom shaft 27 of the loom. By means of upper and lower gears 28 and 29, respectively, see Fig. 2, the top and bottom shafts 13 and 27, respectively, are driven in the usual relation, the top shaft making two rotations for each rotation of the bottom shaft.

By reason of the gearing shown at the lower left hand part of Fig. 1 the cam 23 completes a rotation every four picks of the loom. This cam has a high dwell 30 and a low dwell 31 connected by inclines 32. The effect of the cam 23 is to hold the boxes 16 and 17 in elevated position with respect to the lay for two picks and then to permit the boxes to move down for the following pair of picks. In this way each shuttle box is rendered active for two consecutive picks and then inactive for the next two picks.

Referring particularly to Fig. 2, the bottom shaft 27 has mounted thereon at the other side of the loom another box lifter cam 35 having high and low dwells 36 and 37, respectively, connected by inclines 38. A cam lever 39 similar to lever 20 is pivoted at 40 to the loom frame and is connected to a two part link 41. This link cooperates with a stud 43 on the lever 39 and is pivotally connected indirectly, as at 44, to the bottom of the lifter rod 42. The cam 35 moves with a gear 47 meshing with a gear 48 of half its size, and since the latter gear is secured to the bottom shaft 27, the cam 35 makes a complete rotation every four picks of the loom.

The cam 35 is set so that its inclines 38 operate to shift top and bottom boxes 50 and 51 supported by the rod 42 at a time when the boxes shown in Fig. 2 at the opposite side of the loom are at rest. In other words, the cams 23 and 35, while each rotating in four picks of the loom, are operative to shift their respective boxes at different times so that the boxes at one end of the loom are at rest with respect to the lay while the boxes at the other end are shifting. I do not wish to be limited to this particular mode of setting the cams 23 and 35 in the practice of all features of my invention, but I have found that the shuttle sequences produced by such a shift are convenient for the purposes of my present invention.

In Fig. 5 there are set forth twelve different positions of the shuttle boxes, together with three weaving shuttles which are placed in picking position by the boxes according to a definite sequence. The shuttle race R is indicated diagrammatically as defining the path along which the shuttles travel across the loom. Pickers P and picker stick S are indicated diagrammatically in Figs. 1 and 2 to propel the shuttles which are in picking position, as usual.

For purposes of description, it may be assumed that the shuttles and boxes start as shown in position I, Fig. 5, where shuttles S' and S² are at the right hand shuttle changing side of the loom with boxes 50 and 51 in low position, and shuttle S³ is in the low box 17 at the opposite detecting side of the loom, shuttle box 16 being opposite

the race ready to receive a shuttle. The positions shown in Fig. 5 are indicated with the lay approximately at bottom center, at which position the active shuttle is supposed to have been just boxed so that the shifting of the shuttle boxes can start.

The box shift which follows the bottom center indicated in position I places the boxes and shuttles in position II, where the boxes at the right hand side are raised so that shuttle S² can be picked into box 16, leaving box 51 opposite the race.

On the next shift of boxes indicated in position III the left hand boxes rise so that shuttle S³ can be picked into bottom box 51, leaving box 17 opposite the race.

As shown in position IV the left hand boxes remain up but the right hand boxes have been lowered so that S' can be picked from box 51 which is left opposite the race into the left hand box 17.

Position V shows the left hand boxes lowered so that shuttle S² is moved into action and is picked to the right into the top box 50.

Position VI shows the right hand boxes raised to position shuttle S³ for picking into the top box 16 at the left hand side.

In position VII the left hand boxes have been raised to pick shuttle S' to the right side into box 51, leaving box 17 opposite the race.

In position VIII the boxes at the right hand side are lowered and shuttle S² is picked from box 50 across to the left hand lower box 17.

In position IX the right hand boxes remain in down position but the left hand boxes are lowered so that shuttle S³ can be picked out of the top left box 16 into the top right box 50.

In position X the right boxes are raised so that shuttle S' is picked from box 51 to the left hand upper box 16.

In position XI the left boxes are raised to place lower box 17 opposite the race so that shuttle S² can be picked from it into the lower box 51 at the right hand side.

In position XII the left boxes are retained as they were in position XI but shuttle S³ is placed opposite the race by lowering the right boxes and is picked into the bottom box 17.

Position XIII is the same as position I and it is therefore seen that after a sequence of twelve picks the shuttle gets back into the same relative position with respect to the shifting boxes.

It will be seen by inspecting the different positions of Fig. 5 that at regular intervals each shuttle will appear at a given point or position in the sequence. As shown in position IV, for instance, shuttle S² is in raised position in box 16 and four picks later shuttle S³ is in box 16 in raised position as shown at VIII, and in position XII shuttle S' is in the raised top box 16. This sequence of shuttles is well-known in non-automatic looms and is used for instance in looms for weaving paper machinery felts and also on cam worsted looms. It will be seen that each shuttle is active for but one pick at a time. An auxiliary shuttle box 60 is shown diagrammatically in Fig. 5 but it is normally inactive and does not enter into the normal sequence.

The detecting mechanism shown in Figs. 1, 3, and 4, comprises brackets 65 secured to the lay and extending backwardly therefrom to support small shaft 66. Detector arm 67 is secured to the shaft 66 and has a detector 68 through the body of which extends a pair of electric detector prongs 69 and 70, respectively, insulated from

each other by the material of which the body is made. These prongs are indicated in Fig. 4 as connected electrically to lead wires 71 and 72, respectively, and when they are electrically connected at weft exhaustion, the following circuit is established, see Fig. 10: Source of electric power E, lead wire 72, prong 70, metallic ferrule 86 on bobbin 85, prong 69, lead wire 71, solenoid 73, and wire 74 back to the source E. This energization of the solenoid initiates a shuttle change motion of parts to be described.

In order to time the operation of the detector there is secured to the inner end of the shaft 66 an actuating arm 75 attached to the upper end of an operating rod 76. This latter rod is connected to a lever 77, see Fig. 1, having a roll 78 to rest on a cam 79. Cam 79 is secured to the shaft 25 and completes a rotation over four picks of the loom and this cam has a high dwell 89 which may extend around the greater part thereof. A low dwell 81 is so timed with respect to the box movements at the detector end of the loom as to dip the detector into the top shuttle box 16 when the lay is rearmost just preceding that position of the sequence in which box 16 is to move down from inactive to active position. The shuttle contained by box 16 will therefore be rendered active to be picked across to the magazine side of the loom shortly after its condition of weft has been detected.

The time of starting the descent of the detector need not be exactly as described, but should be such as to permit completing of the circuit already described in sufficient time to permit energization of the solenoid some time prior to the time that lifting of the boxes at the magazine end of the loom can start. While I have designated this position as with the lay at back center, yet it could if desired occur when the lay is at some point between top and back center.

It is to be understood that the downward movement of the boxes will pull the exhausted shuttle away from the detector and that the box 16 will be in low position for two picks. Hence there is no necessity for a quick return of the detector to its elevated inactive position. This restoration of the detector to its normally raised inactive position can occur at any time prior to a subsequent rising of a shuttle in box 16.

At the opposite end of the loom from the detector there is provided a shuttle changing mechanism including a magazine M having a single stack of reserve shuttles SR arranged one over the other. This magazine may be supported by a bracket 90 secured to the loom frame and the lowermost shuttle rests on a platform or plate 91 swinging about pivot 92 on the magazine. A set screw 93 on lever 94 which pivots about center 92 and carries the plate 91 is positioned for engagement with a boss 95 secured to the shifting shuttle box structure which includes the cells 50 and 51. The previously mentioned auxiliary shuttle box 60 is located below the cell 51 and all three of these boxes or cells are supported by and give vertical movements through action of rod 42. A light spring 96 acts to move the plate 91 back to normal position after transferring movement.

A single binder 97 is substantially fixed to the lay to cooperate with the shuttle box which is in active picking position, see Figs. 8 and 9. The binder has top and bottom horns 98 and 99, respectively, which cooperate with the cells above and below the race plate R.

A box cover 100 for cell 50 is pivoted as at 101 to a part of the box and has a lug 102 to engage 75

a cam 103 on the magazine frame when the boxes are in their highest position.

Box rod 42 normally receives movements from the cam 35 to shift cells 50 and 51 so that they will take part in the previously described sequence but this rod is also subject to an additional lifting movement at the time of shuttle change through the action of a lifter latch 105 pivoted to a regularly moving lever 106 moving about the center 40. Lever 106 is moved by a cam 107 secured to the shaft 25 so that it completes a revolution every four picks of the loom. This cam is shaped substantially as shown in the lower part of Fig. 2 and has a low dwell 108 which holds the latch down when the shifting shuttle boxes 50 and 51 are in their low position. The cams 35 and 107 turn in the direction indicated at arrow *a*, Fig. 2, and a lifting surface 109 on cam 107 leads from the dwell 108 to a high dwell 110. The cams are so related that the lifter surface 109 comes into action to elevate the latch during those picks of the sequence when cell 50 would normally be in line with the race to receive the shuttle coming from the detector side of the loom.

In operation, the pairs of weaving boxes at the two ends of the loom will shift in regular order to render the three shuttles active as described. Every fourth pick the detector will descend when there is a shuttle in box 16 and the latter is raised. This may occur, for instance, when the loom is between the positions III and IV just before the detected shuttle becomes active. The latch 105 and its lever rise regularly at four pick intervals, being all the way up when the shuttle from box 16 reaches the magazine side. So long as enough weft is present in all the shuttles this sequence continues without interruption.

When an empty shuttle is raised by box 16 toward the detector and the latter has descended, a condition will exist such as that shown in position VIII of Fig. 5, where it is assumed that shuttle S³ is being detected and is depleted. The detector will act to close the previously traced circuit and cause the solenoid to throw the latch from the full to the dotted lines in Fig. 10, the latch and its lever being in low position at this time. During the time that the lay is in the forward half of its movement and when shuttle S³ is being lowered from position VIII to position IX there will be simultaneously a raising of the boxes at the right hand side of the loom so that boxes 50, 51 and 60 will be in the position designated at IX—A, Fig. 5, with auxiliary box 60 aligned with the race. The depleted shuttle S³ will therefore enter this latter box when arriving at the right hand side of the loom.

It is to be understood that the shuttle is picked when the lay is moving rearwardly and in so-called top center or midway position and that the boxes are in the position IX—A prior to the picking. As the lay moves rearwardly, therefore, the projection 102 will be placed to engage cam 103 to lift the cover of the box 50 and lug 95 will be placed to engage the screw 93 to move the plate 91 rearwardly, and as the lay reaches its rearmost position the bottom reserve shuttle of the magazine will drop into the top box 50. It is this box 50 which shuttle S³ would normally enter were its supply unexhausted, and it will be seen therefore that by applying a fresh shuttle into this box the sequence can be reestablished after the temporary interruption accompanying shuttle change.

The boxes at the magazine end of the loom will

remain in their highest position until the lay reaches bottom center, after which these boxes will be lowered one step by action of surface 112 on cam 107 and lever 106 so that box 51 is aligned with the race. Since shuttle S³ was last picked it is now the turn of shuttle S² to be picked and this shuttle is in the middle box 51. This one-step down motion, which is as slow and easy as the usual box shift will therefore place shuttle S² in picking position so that it will be driven to the left hand side of the loom as indicated in position X. The boxes at the magazine side of the loom remain in this position for another pick, lever 39 having returned to high dwell 36 to be supported thereby as the latch continued down, so that shuttle S² can be picked back to the magazine side as indicated in position XI, whereupon box 50 is lowered to render new shuttle S³ active.

It is this downward movement of the boxes to place the freshly inserted shuttle into action 20 which lowers auxiliary box 60 and depleted old shuttle S³ to discharging position below the depending prongs of the binder. On the forward motion of the lay, therefore, the depleted shuttle will be ejected forwardly into any form of receiver not shown. This particular mode of ejecting the exhausted shuttle, as well as the mechanism for applying a fresh reserve shuttle to the box 50, may be as set forth in my copending application Serial No. 460,746 and the magazine and associated parts may if desired be more particularly as shown in Chevrette Patent No. 1,834,302.

During the actual transfer of the shuttle from the magazine to the box 50 the lowest reserve shuttle together with all those resting on it will drop when the plate 91 is in back position. As the lay moves forwardly, however, the plate 91 will advance to move under the next lowest magazine shuttle before the latter is entirely unsupported by the shuttle being changed.

While I have shown the weft detector as associated with the top box on the left hand side of the loom, yet I am not necessarily limited to this position of the detector inasmuch as it could be placed to detect in the bottom shuttle on the left hand side if desired. A corresponding reversal of the movements of the boxes at the right hand side of Fig. 5 would place the shuttles correctly for operation under this alternative arrangement. The point to be borne in mind is that the shuttle which is being detected when next active should be picked into the top box at the magazine side of the loom.

From the foregoing it will be seen that I have provided a shuttle changing loom wherein each of three shuttles is active for but one pick at a time according to a predetermined normal sequence and that means are provided for interrupting this sequence at the time of weft exhaustion to move one of the normal weaving boxes which is temporarily empty into receiving relation with respect to the magazine, and to place a normally inactive auxiliary box in position to receive the exhausted shuttle. By two separate subsequent single box downward motions the boxes at the magazine side act first to permit picking of the shuttle which is in box 51 and unaffected by transfer and then the freshly inserted shuttle is rendered active and the depleted shuttle expelled. These two steps avoid a quick two box shift which might interfere with proper shuttle changing motions. The outgoing shuttle is moved forwardly so that its thread which extends to the selvage does not cross the path of the active shuttles, and the freshly inserted re-

serve shuttle is fully threaded so that the tension of the first pick is normal. No selvage cutter has been set forth herein but any of the well-known mechanisms of this type can be employed 5 and can be set to cut at any desired time without regard to the replenishing interval.

I have found that under certain conditions the shuttles which are in boxes 50 and 60 may tend to move inwardly toward the cloth when these 10 boxes are not opposite the stationary binder. In order to prevent such a creeping of the shuttles I provide a roll carrier 120, see Figs. 8 and 9, having upper and lower rolls 121 and 122, respectively, which are urged toward the shuttles by a 15 light spring 122. This spring may be secured to the stationary binder as shown in Fig. 9 and is forked to straddle a boss 123 on the binder passing through an opening in the carrier 120. By this arrangement the carrier is permitted a certain 20 freedom of motion and the rolls can be made of some friction material such as rubber to exert a slight resistance to endwise motion of the shuttles.

Having thus described my invention it will be seen that changes and modifications may be made 25 therein by those skilled in the art without departing from the spirit and scope of the invention and I do not wish to be limited to the details herein disclosed, but what I claim is:

1. In a shuttle changing loom, a lay, a reserve 30 shuttle magazine adjacent one end of the lay, three shifting shuttle boxes on said lay each capable of being moved into active position with respect to the lay, and a single binder substantially stationary with respect to the lay to co- 35 operate with any box in active position, said binder having parts to extend upwardly into operative relation with one of the shuttle boxes above active position and having other parts to extend downwardly into operative relation with 40 the other shuttle box when the latter is below active position.

2. In a shuttle changing loom, a lay, a reserve 45 shuttle magazine adjacent one end of the lay, three shifting shuttle boxes on said lay each capable of being moved into active position with respect to the lay, a single binder substantially stationary with respect to the lay to cooperate with any box in active position, and means supported by and movable relatively to the binder to prevent shuttles in the adjacent inactively positioned boxes from moving longitudinally.

3. In a shuttle changing loom operating with 50 a plurality of weaving shuttles, a lay, a reserve shuttle magazine adjacent one end of the lay, three shifting shuttle boxes on the lay each movable to active position relatively to the lay and one of said boxes capable of receiving a reserve shuttle from the magazine, a single binder on the lay to cooperate with any shuttle box in active 55 position, a carrier on the binder extending above and below the latter, and a pair of shuttle engaging rolls on the carrier, one above the binder to cooperate with a shuttle in a box above the lay and the other below the binder to cooperate with a shuttle in a box below the lay.

4. In a shuttle changing loom operating with 60 a plurality of weaving shuttles, a lay having a shuttle race, a reserve shuttle magazine adjacent the shuttle boxes, three shuttle boxes each movable relatively to the lay to active position opposite the shuttle race, a single binder supported by and substantially stationary with respect to the lay, a carrier on the binder, a roll on the car- 65 rier positioned to cooperate with a shuttle in a

shuttle box above the race, a second roll on the carrier to cooperate with a shuttle in a shuttle box below the race, the lowest box being below the second roll to permit a shuttle to move out of said box transversely of the latter when the boxes 5 are in lowest position, and the top box being above the first roll to receive a reserve shuttle from the magazine when the lowest box is in active position.

5. In a shuttle changing loom operating with 10 a plurality of weaving shuttles, a lay having a shuttle race, a reserve shuttle magazine adjacent the shuttle boxes, three shuttle boxes each movable relatively to the lay to active position opposite the shuttle race, a single binder supported by 15 and substantially stationary with respect to the lay, a carrier on the binder, an element on the carrier above the binder to cooperate with a shuttle in a shuttle box next above the box in active position, a second element on the carrier below 20 the binder to cooperate with a shuttle in a shuttle box next below the shuttle box in active position, the lowest shuttle box being below the second element when the top box is active to permit forward ejection of a shuttle from the lowest 25 box, and the top shuttle box being above the first element to receive a reserve shuttle from the magazine when the lowest shuttle box is active.

6. In a shuttle changing loom having a lay 30 with a shuttle race and operating with a plurality of weaving shuttles, three shifting shuttle boxes movable relatively to the lay so that each box is movable to active position relatively to the shuttle race, a single binder mounted on the lay and substantially stationary with respect 35 thereto and located to cooperate with any shuttle box actively placed with respect to the shuttle race, a carrier supported by and movable relatively to the binder, a spring carried by the binder and holding the carrier yieldingly toward 40 the shuttle boxes, an upper friction element supported by the carrier to extend above the binder and cooperate with a shuttle box next above the box in the active position, a lower friction element supported by the carrier to cooperate with 45 a shuttle box in the position next below a shuttle box in active position, said shuttle boxes shiftable to present the lowest shuttle box in active position and raise the top box above the upper 50 friction element to receive a reserve shuttle, said shuttle boxes thereafter shiftable to lowest position with the top shuttle box active and with the lowest shuttle box below the lower friction element to permit forward discharge of a shuttle 55 from the lowest box.

7. In a shuttle changing loom having a lay 60 with a shuttle race and operating with a plurality of weaving shuttles, a reserve shuttle magazine, three shuttle boxes shiftable relatively to the lay and each movable into active position with respect to the shuttle race, a single binder carried by the lay to cooperate with the shuttle box in active position, means supported by and extending vertically in opposite directions from 65 the binder to cooperate with those shuttles only which are in shuttle boxes adjacent active position, the top box being movable vertically to a position above that position adjacent the active position to receive a reserve shuttle from the 70 magazine, and the lowest shuttle box movable to a position below the shuttle box adjacent and below the active position for the ejection forwardly of a depleted shuttle.

8. A loom binder for an intermediate box of a 75

gang of shuttle boxes having a box above and another box below the intermediate box, said binder having a body and a carrier extending above and below the binder and supported by 5 the latter, a friction element supported by the carrier in a position above the binder, and a sec-

ond friction element supported by the carrier in a position below the binder, the friction elements being positioned to engage shuttles in boxes adjacent to the intermediate boxes.
